CLAIM

The ornamental design for a low voltage connector barrel for lithium ion battery module, as shown and described.

DESCRIPTION

FIG. 1 is an overhead perspective view of a low voltage connector barrel for lithium ion battery module, showing our new design;

FIG. 2 is a front elevational view thereof;

FIG. 3 is a front bottom perspective view thereof;

FIG. 4 is a front overhead perspective view thereof;

FIG. 5 is a front right side perspective view thereof;

FIG. 6 is a front left side perspective view thereof;

FIG. 7 is a rear elevational view thereof;

FIG. 8 is a bottom perspective view thereof;

FIG. 9 is a rear overhead perspective view thereof;

FIG. 10 is a rear bottom perspective view thereof;

FIG. 11 is a rear left side perspective view thereof;

FIG. 12 is a rear right side perspective view thereof;

FIG. 13 is a top plan view thereof;

FIG. 14 is a bottom plan view thereof;

FIG. 15 is a right side elevational view thereof; and,

FIG. 16 is a left side elevational view thereof.

The broken lines shown represent unclaimed subject matter only and form no part of the claim. Where the dot-dash broken lines abut the shaded surface it is understood that those broken lines represent an unclaimed boundary between claimed and unclaimed surfaces. None of the broken lines form any part of the claimed design.

1 Claim, 8 Drawing Sheets
